[57] CLAIM

The ornamental design for a plasma transfer bottle, substantially as shown and described.

DESCRIPTION

FIG. 1 is a perspective view of a container for collections and transfer of plasma and other sterile liquids showing my new design;

FIG. 2 is a front elevation view of the container;

FIG. 3 is a top plan view thereof;

FIG. 4 is a side elevation view thereof; and

FIG. 5 is a bottom plan view thereof.

*Fig. 1**Fig. 2**Fig. 3**Fig. 4**Fig. 5*
